CONCRETE PIPE

Charles F. Buente, Scott Township, Allegheny
County, Pa.

Application March 12, 1940, Serial No. 323,567

4 Claims. (Cl. 138—84)

This invention relates to concrete pipe and, in particular, to that class of the product known as drainage pipe, i. e., pipe of relatively large diameter adapted to be buried at substantial depths.

Concrete drainage pipe has been made heretofore in various shapes and sizes but the standard product is cylindrical, is provided with reinforcement of various kinds, and has a wall thickness varying with the inside diameter of the pipe. The present standards and formulas for the design of reinforced concrete pipe to sustain given loads, are based on an investigation made thirty years ago. These formulas have been generally adopted by pipe users and makers. The wall thicknesses now embodied in standard specifications for various sizes and classes of pipe were derived from the results of this investigation. Prior to that time, the accepted test for the strength of concrete pipe was to determine whether the load for which each size and grade of pipe was designed, caused a crack extending the full length of the pipe. Because of the difficulty in meeting this test, it was modified in the standard specifications to permit a crack having a width up to .01". These cracks in reinforced concrete pipe as now made, are accepted as unobjectionable because they cannot be avoided but do, nevertheless, seriously impair the utility of the pipe as a structural unit. The cracks are formed, of course, because the steel reinforcement does not carry any substantial proportion of the stress in the pipe until the concrete has been stressed beyond its ultimate strength.

Concrete pipe as now made is characterized by further shortcomings. Pipe of various sizes designed by present standards, when tested, exhibits a load-bearing capacity which is seemingly without relation to the specifications according to which it is made. A tabulation of numerous tests on various sizes and types of pipe indicates that the maximum load at which the standard cracking test was met, was virtually the same for all pipe in the range of sizes from 36" to 66", and that there is only a small variation in the ultimate load capacity of the pipe in the several classes. The relative strength of the pipe, furthermore, appears to be greater in the smaller sizes.

A further shortcoming of reinforced pipe as now made is that an increase in the amount of reinforcement does not produce a proportional increase in the load-bearing capacity. As a matter of fact, the load-bearing capacity is increased only to the extent of from 14% to 47% of the

increase in the amount of reinforcing, for certain selected sizes of pipe.

I have invented a novel form of concrete pipe which overcomes the aforementioned objections to pipe as now made. A preferred embodiment of the invention comprises a plain concrete pipe, the exterior of the section of which is generally oval, with a wall thickness varying from a maximum at the top and the bottom of the pipe to a minimum at the sides. The pipe is preferably designed on the basis of the strength of concrete alone in tension and compression and ordinarily no reinforcement is required. Some reinforcement may be employed if desired, in order to provide an increased factor of safety. The invention provides a pipe which, in all sizes, has the relatively high load-bearing capacity of the smaller sizes of pipe as made heretofore. Pipe according to the invention, furthermore, may be designed for increased load-bearing capacity in the larger sizes. The pipe of my invention, finally, will not exhibit cracks when loaded, within the limits for which it is designed, and will have an ultimate strength providing an adequate margin of safety.

The following detailed description and explanation of the invention should be read with reference to the accompanying drawing illustrating several forms of the preferred embodiment outlined above, as well as diagrams useful in explaining my analysis of the theory underlying the performance of my invention. In the drawing,

Fig. 1 is a transverse section through one form of pipe according to the invention;

Fig. 2 is a similar view showing a slightly different form of pipe;

Fig. 3 is a similar view showing a still further different form of pipe;

Fig. 4 is a diagram illustrating the stress created in an ordinary cylindrical pipe when loaded; and

Fig. 5 is a vector diagram showing the forces existing at a given point in the pipe.

Referring now in detail to the drawing, the pipe 10 shown in Fig. 1 has a section the exterior of which is defined by the oval 11 having a major axis 12 and a minor axis 13. The interior of the pipe section is defined by a circle 14 having its center at the intersection of the axes 12 and 13 of the oval 11. The pipe 10 thus has a wall thickness which varies from a maximum at the top and bottom to a minimum at the sides. The pipe shown in Fig. 1 is particularly adapted for small sewer pipe and may be made in various sizes, without reinforcement. For an inside di-

ameter of 24" the maximum wall thickness should be about 4" and the minimum about 2". The ends of the pipe may be suitably formed to provide any desired type of joint, e. g., the ordinary bell and spigot joint. The pipe may be made by known methods and apparatus, the only change in the latter being in the shape of the form.

Fig. 2 illustrates a slightly different form of pipe 15. The section of the pipe 15 is defined by concentric ovals 16 and 17 having their major and minor axes 18 and 19 in alignment and intersecting at a common point. The major and minor axes of the oval 16 differ by substantially the same amount from the diameter of a circle of substantially the same area. The major and minor axes of the oval 17 are such, relative to those of the oval 16, that the pipe 15 has a wall thickness which is a maximum at the top and bottom of the pipe as indicated at 20, and a minimum at the sides of the pipe, as indicated at 21. The wall thickness, furthermore, varies substantially continuously between the points 20 and 21.

The pipe 15 in a size corresponding to a cylindrical pipe having an inside diameter of 60", has a minimum inside diameter of 52" and a maximum inside diameter of 68". The maximum wall thickness, furthermore, is 8" and the minimum wall thickness, 5". With these dimensions, the pipe is capable of carrying a load of 2000 pounds per square foot of projected area, when laid with the axis 13 vertical, with a margin of safety of 1 to 1½. When loaded within the limit mentioned, furthermore, the pipe does not exhibit cracks, because the stress (both tension and compression) applied to the concrete by such loading is less than the ultimate strength thereof.

The ends of the pipe 15 may, as previously indicated, be formed to provide bell and spigot joints.

Fig. 3 illustrates extra-strength pipe embodying my invention. The pipe 22 will withstand a load of 4000 pounds per square foot of projected area when laid with its major axis vertical. The major and minor axes of the inner oval 23 thereof are the same as those of the pipe 15. The maximum wall thickness of the pipe 22 is 9½" and the minimum thickness, 6". The load-bearing capacity stated for pipe having the dimensions given is based entirely on the ultimate strength of the concrete. At loads within the stated value, therefore, no cracks will be formed in the concrete. To take care of occasional excessive loads and provide a factor of safety of from 1 to 1½, I employ light steel reinforcement 24. For the pipe shown, the section of each of the two cages should amount to about .25 square inch per lineal foot of pipe. Cracks will result, of course, when the pipe is loaded beyond its rated capacity.

Concrete pipe embodying my invention is characterized by numerous advantages. In the first place, the high degree of curvature of the pipe adjacent the top and bottom gives it the relatively high load-bearing capacity characterizing the smaller sizes of cylindrical pipe as made heretofore. The load-bearing capacity of the pipe of my invention, furthermore, may be increased in the larger sizes by making the wall thickness greater. The invention also provides a concrete pipe which is not subject to cracking with all its attendant disadvantages, so long as the load is not greater than that for which the pipe is designed. The possibility of omitting reinforcing makes the pipe of my invention con-

siderably cheaper than ordinary reinforced concrete pipe. The manufacturing operations necessary for producing the pipe of my invention, furthermore, are not substantially different, nor any more expensive than those by which conventional pipe is made.

The section of the pipe of my invention has a width about 15% less than the diameter of cylindrical pipe of about the same sectional area. As a result, the area per unit length of pipe, which is projected on a horizontal plane is less than that of a cylindrical pipe. My pipe may, therefore, be designed for a lower earth load than that for which cylindrical pipe of the same flow capacity must be calculated. Not only is the total earth load reduced, but the moment arm or span is similarly reduced. The actual bending moment is thus reduced by the square of the reduction in width of section, or about 22%.

By making the pipe thicker at the top and bottom, where cracks normally appear in ordinary concrete pipe, I provide greater strength to resist the increase in effective vertical load which occurs when outward deflection of the sides is arrested by lateral earth pressure.

The advantages of the invention pointed out above may, in my opinion, be explained by the following analysis of the stresses involved, although I do not wish to be bound by any theories of performance as stated herein.

Referring to Fig. 4, showing diagrammatically and for the purpose of explanation only, the upper half of a plain, unreinforced, cylindrical concrete pipe 25, the stresses set up therein by the application of the load L are as indicated by the arrows. At any vertical section there is a vertical shearing force S₁. Tension T and compression C exist in the fibers of the shell spaced from the neutral axis N. The compression and tension are interchanged in passing the points of contraflexure CF at which the tension and compression are zero. The longitudinal shearing force S₂ representing the resistance of successive layers of the concrete to the force tending to slide one over the other, is tangential to the neutral axis at the plane of any section through the pipe wall.

Following the analysis given by Hool, Reinforced Concrete Construction vol. I, p. 44, the vector diagram shown in Fig. 5 may be drawn to represent the forces at a point P in the neutral axis, the vertical and tangential shear at any point being equal (op. cit., p. 43). The vertical shear S₁, combined vectorially with the tangential shear S₂, produces resultant tension T₁ and compression C₁ perpendicular to the neutral axis N and tangential thereto, respectively. The compression C₁, however, is not equal to the tension T₁, as in Fig. 14 on page 44 of Hool. On the contrary, the compression C₁ is much greater than the tension T₁ and this compression acts directly to resist the effect of the load. It is thus apparent that there exists in a concrete pipe an active shear resistance. This force, together with the force developed by the resistance to bending, constitutes the total strength of the pipe.

The pipe of my invention, by having the maximum curvature at the top and bottom, obtains the greatest benefit from this shear resistance. By reason of the oval shape, the pipe of my invention has a shear resistance which is much greater than that which is effective in a cylindrical pipe of the same sectional area.

By numerous tests, I have determined that the

bending strength or modulus of rupture of the concrete in conventional reinforced concrete pipe is about 450 pounds per square inch. By the use of known formulas, it is possible to determine from this figure the load carried by the bending resistance offered by any given pipe. After proper allowance for the small resistance to the formation of a crack in the concrete offered by the reinforcement, it is found that a 48" plain concrete pipe with a wall thickness of 5", has an ultimate concentrated load strength of 4100 pounds. The portion of the load carried by the bending resistance, determined as above mentioned, is, however, only 2650 pounds. The difference, or 1450 pounds, appears to be carried by the excess of the compression C_1 , (Fig. 5) over the tension T_1 . The following table gives similar figures for various other pipe sizes:

Size of pipe	Shell thickness	Strength	Bend-ing resist-ance	Total	Shear resist-ance	Total
Infinite (straight beam)	Inches	Pounds	Pounds	Per cent	Pounds	Per cent
66"	6½	4100	4100	100	0	0
60"	6½	4100	3280	80	820	20
60"	6	4100	3070	75	1030	25
54"	5½	4100	2860	70	1240	30
48"	5	4100	2650	65	1450	35
49"	4½	4100	2450	60	1650	40
36"	4	4100	2300	55	1800	45
30"	3½	4100	2060	50	2040	50
0 (solid)	0	4100	0	0	4100	100

To design pipe according to my invention, for various loads, I start with the inside diameter of a cylindrical pipe necessary to give the desired free sectional area. The major and minor axes of my oval pipe are then obtained by increasing and decreasing this diameter by about the same amount, e. g., in the embodiment of Fig. 2, 8". The sectional area of the oval pipe thus obtained differs but slightly from that of cylindrical pipe of the starting diameter. I then determine from the above table, the load capacity of the pipe due to shear resistance, picking the value for shear resistance to correspond with the radius of curvature of the pipe at the top and bottom. The balance of the load for which the pipe is being designed must be carried by the bending resistance. Using standard structural formulas, and basing the bending resistance on the modulus of rupture of the concrete, i. e., about 450 pounds per square inch, the wall thicknesses along the major and minor axes may then be determined. These will determine the dimensions of the exterior of the pipe.

As stated above, pipe designed in this manner will support its standard load without the formation of cracks. Since the design is based on the strength of the concrete represented by its modulus of rupture, the tensile stress in the concrete has no further leeway and it is desirable, therefore, to provide some light reinforcement as indicated at 24 in Fig. 3, which, with the shear resistance which is still effective, will produce the additional strength needed to provide a suitable safety factor.

Although I have illustrated and described herein but a preferred embodiment of the invention, it will be understood that changes in the details thereof may be made without departing from the spirit of the invention or the scope of the appended claims.

I claim:

1. Concrete drainage pipe having a cross sec-

tion which is generally oval on the exterior and interior and a wall thickness varying substantially continuously from a maximum at the top and bottom to a minimum at the sides.

2. Concrete drainage pipe having a generally oval section and a wall thickness varying from a maximum at the top and bottom to a minimum at the sides, the wall of said pipe being so dimensioned that the concrete will withstand any stress created therein by loads below the maximum for which the pipe is designed.

3. Concrete drainage pipe having a generally oval section, the horizontal and vertical interior dimensions of the section differing substantially equally from the diameter of a circle having approximately the same area, the vertical dimension being greater and the horizontal dimension less than said diameter, the wall thickness of the pipe being greater at the top and bottom than at the sides.

4. Concrete drainage pipe as defined by claim 2 characterized by a circular bore.

CHARLES F. BUENTE.
